UNITED STATES PATENT OFFICE.

EDGAR J. ROSE, OF LOS ANGELES, CALIFORNIA.

HIGH-TENSION DISCHARGE APPARATUS.

996,280.

Specification of Letters Patent. Patented June 27, 1911.

Application filed June 28, 1909. Serial No. 504,901.

To all whom it may concern:

Be it known that I, EDGAR J. ROSE, a citizen of the United States, residing at Los Angeles, in the county of Los Angeles and 5 State of California, have invented a new and useful High-Tension Discharge Apparatus, of which the following is a specification.

One object of the present invention is to provide an apparatus adapted for use with 10 direct or alternating current which does not require for its use any special knowledge or skill by the operator.

Another object of the invention is to provide an apparatus for the stated purpose 15 which can be used to produce oscillatory current of differing character, particularly with regard to the frequency and intensity of the current.

Another object of the invention is to provide 20 a high tension apparatus in which maximum prolongation of the period of closure of circuit is provided, whereby I am enabled to cause efficient energization of a self-induction coil of large inductance under 25 high periodicities.

The accompanying drawings illustrate the invention, and referring thereto:

Figure 1 is a diagram of the circuit connections, the controlling switches being 30 shown in plan. Fig. 2 is a horizontal section of the circuit-controlling electro-magnetic device. Fig. 3 is a partial elevation thereof. Fig. 4 is a side elevation of the controlling switch means for connecting the 35 apparatus to direct or alternating circuit.

The apparatus comprises a primary circuit provided with means for connection to either alternating or direct supply circuit with electro-magnetically operated circuit 40 controlling means, self-induction means and a condenser for producing electric oscillations in the primary circuit, and a secondary circuit in inductive relation to the primary circuit.

The circuit connecting means comprises 45 two switches 1, 2, adapted respectively for operation with direct or alternating current, the switch 1 is a double throw switch for reversing polarity or maintaining a given 50 polarity, irrespective of the direction of the direct current in the circuit to which it is connected. Each of the switches 1, 2 may be of the construction shown in Figs. 1 and 4, comprising an insulating plate or bar 4, pivotally mounted at 5 on standards 6, a leaf 55 spring 7 being fastened at its middle to the

mid-length of said plate 4 and with its end portions springing free from said plate, so that these end portions bear against the standards 6 to make a bond or contact therewith and the outer ends of said spring means 60 7 bear against the fixed contacts 8 of the respective switches to maintain efficient contact therewith.

In order to prevent both of the switches 1, 2 from being operated simultaneously an interlocking means is provided consisting, for example, of a frame or bar 10 slidably mounted on the base 5 of the apparatus and having a handle 11 and one or more projections 12 so placed that a projection 12 is always under one or the other of the switch members 4, so that both can not be brought into closed position simultaneously. The fixed contacts 8 of the switch 1 are connected respectively by wires 13 to terminals 14 for a direct current circuit. Posts 8, 6 on one side of the switch 2 are connected by wires 17 to a terminal 15 for an alternating supply circuit, said wire 17 including the 80 primary coil 18 of a transformer. The secondary coil 19 of said transformer is connected to a circuit 20 including the posts 8, 6 on the other side of said switch 2, so that when the switch is in closed position the two 85 plates 7 thereof close the primary circuit of the transformer and the secondary circuit of said transformer. The secondary circuit 20 of the transformer is connected as a branch to the main primary circuit 23 which also 90 has branch connections 24 from the respective sides thereof to the posts 6 of the direct current switch 1. In one side 25 of the main primary circuit are included the self-induction coil or inductance means 21, and the coil 95 27 of an electro-magnet, whose armature 30 operates an automatic circuit controller 28, 29 connected in a circuit 31 extending between the two sides 23, 25 of the main primary circuit. A discharge circuit 16, 100 connected to the two sides of the main circuit at opposite sides 29, 30 of the circuit controller, includes a condenser and the primary coil 33 of the high tension transformer whose secondary 34 is connected in a high tension discharge circuit 35 provided 105 with the electrodes 36. The primary of this transformer may be further provided with a supplementary winding 37 having the same number of turns as the main winding 110 33, but of less cross section, so as to present a higher resistance.

The condenser is formed in two sections 38, 39, section 38 being larger, or of greater capacity, and means are provided for connecting said sections separately, in series, or 5 in parallel in the discharge circuit, said means consisting of a plug switch provided with three split contact-sockets 40, 41, 42. One side of socket 40 is connected by wire 43 with one side of socket 41, the other side 10 of socket 40 being connected by wire 44 to one side of socket 42. The other side of socket 41 is connected to circuit wire 16 and to one side of condenser 38, the other side of said condenser being connected by wire 45 to 15 wire 44. The other side of socket 42 is connected to a wire 16' completing the circuit to the transformer, said wire being connected to one side of condenser 39 the other side of which is connected by wire 46 with wire 43. 20 Two plugs, indicated at 50, 51, are provided. By placing a plug 50 in the socket 40 the condensers are connected in series with the discharge circuit, this being the condition of least capacity, producing the highest frequency and smallest quantity of discharge. 25 By placing the plug 51 in the socket 41, the condenser 38 is shunted, so that condenser 39 is connected alone in the circuit. By placing the plug 50 in socket 40 and plug 51 in 30 socket 42, the condenser 39 is shunted, leaving the condenser 38 alone in the circuit. By placing the two plugs in sockets 41 and 42, leaving the socket 40 open, the two condensers are connected in parallel, these successive connections giving differing capacities which increase in the order stated, the connection in parallel being that of largest capacity corresponding to lowest frequency 35 and greatest quantity of discharge. 40 The electro-magnetic controlling device is preferably of the construction shown in Fig. 2, the coil 27 thereof being wound on a core 53 of magnetic material, for example, laminated iron, said core having a central bore 49, in which slides longitudinally a non-magnetic stem 54 of the armature 30, said armature being formed as a disk fast on said stem. A coil spring 55 within the bore 49 engages with the rear end of the stem 54 45 and with an adjustable screw plug 56 screwing into the rear end of the bore 49 and tends to force the armature 30 away from the operating coil. Contact 28 of the circuit controller is carried by the said stem 54 and contact 29 of said controller is carried by a screw 58 working in a standard 59, said standard being provided with a binding post 60. The standard 59 is preferably laminated for radiation of heat therefrom 55 and laminæ 61, 62 are provided on the screw 58 and on the stem 54 for radiation of heat. It is a characteristic of the form of circuit controller described when connected in the circuit as above stated and when the parts 60 are properly proportioned that its operation

on the circuit is to cause rapid oscillations or variations of the current strength without material interruption of the current. The time of contact or of virtual contact is prolonged at each movement of the contacts to 70 such an extent that the intervening periods of absolute break become negligible. For this purpose it is necessary that the pressure of the return spring 55 should be adjusted by the screw 56, so that the time period of 75 the oscillatory device, constituted by the armature 30, stem 54, and spring 55, is shorter than the period of oscillation of the electric circuit; or, so that at or before the time that the current has died away to zero 80 in any oscillations, the spring 55 will have brought the parts back to normal position, thereby reestablishing the current. By thus prolonging the period of contact I am enabled to provide for efficient energization 85 of self-induction means of relatively large inductance, while operating under high frequencies. A fixed terminal 65 is provided on base 70 of the circuit controller, for connection of the circuit wire 25, and the connection to the stem 54 and contact 28 is made by a flat strip 66 fastened to this terminal and bent in U-shape, with its end attached to stem 54, this strip being of thin metal 90 sufficiently flexible to prevent it from having a substantial effect on the motion of the armature, which is slidably supported in the bore 49 and is movable freely one way by the action of the armature, and the other way by the action of the spring. 95 The apparatus is used as follows: The connections are made to the supply circuit either by the terminals 14 or 15, according to whether the supply circuit is direct or alternating in character. If direct current 100 is being used, switch 1 is operated in one or the other direction according to the direction of the supply current, this being particularly desirable in X-ray work where the direction of the discharge is of importance. The current passes from a terminal 14 through upper wire 13, upper members 8, 7, 6 of switch 1, wires 24, 23, circuit 31, through contacts 29, 28, to coil 27 of the electro-magnet, thence through the self-induction coil 21, through wires 25, 24 and lower members 6, 7, 8 of switch 1 and lower wire 13 to the supply terminal. Electro-magnetic coil 27 then operates the armature 30 to suddenly increase the resistance 110 between contacts 28, 29, so that the self-induction coil 21 is enabled to produce a self-induction discharge of high tension 115 which passes for the most part in the discharge circuit 16 including the primary coil 120 33 of the high tension transformer and a condenser. In the resultant rise of potential at the condenser, a point is reached where the condenser will itself discharge back through the discharge circuit 16 and the 125 130

break or gap at the contacts 28, 29, this condenser discharge being in a circuit exclusive of the self-induction means 21 and therefore of relatively low impedance, so that a discharge of high frequency is produced, the frequency and intensity of the discharge depending upon the connection of the condensers, as above stated.

In using alternating current, the supply circuit is connected to the terminals 15 and the switch 2 is closed, the alternating current passing through the upper members of the switch and through the circuit 17 and the primary coil 18 of the transformer. The current thereby generated in the secondary coil 19 passes through the circuit 20 and lower members of switch 2 to the main charging circuit 23, 25, through which it energizes the self-induction means 21 and the electro-magnetic coil 27, as above described. By properly adjusting the screw 56 of the electro-magnetic circuit controlling device, said device is made responsive to the alternating current in such manner that it quickly adjusts itself to synchronism with the alternating current. In fact, it is found that even before the armature has come into synchronism with the current, there is a tendency for it to take up a condition of synchronism with a multiple period of the current, for example, every third or fourth oscillation, until it finally drops into complete synchronism. By providing the two coils 33, 37 of different resistance in the primary of the transformer, I am enabled to increase the duration of the discharge, as the circuits established through the two coils will have a different time period on account of the difference in resistance so that the current will rise to a maximum in the circuit through the coil of higher resistance before it will rise to a maximum in the other coil, the oscillatory discharges from the two coils, therefore alternating to some extent.

What I claim is:

1. In a high tension discharge apparatus, a charging circuit comprising means for connection of supply current, a self-induction means, and a circuit controller, electro-magnetic means for operating said circuit

controller comprising a coil, an armature controlled thereby and operating the circuit controller, and a spring acting on the armature in opposition to the coil, the time period of the electro-magnetic operating means being shorter than the time period of the charging circuit, so that at each operation the electro-magnetic operating means restores the normal condition before the discharge of the self-induction coil ceases, and a discharge circuit including a condenser and high tension transformer connected to said circuit controller.

2. In a high tension discharge apparatus, the combination with the charging circuit provided with connections for supply current and including a self-induction coil and a circuit controller, of electro-magnetic operating means for said circuit controller the time period of said electro-magnetic operating means being shorter than the time period of the charging circuit therefor, comprising a coil, a core therein, an armature for said core, a stem of non-magnetic material slidably mounted in the core and carrying the armature, whereby the armature is floating supported, a coil spring mounted within the core and engaging with said stem to press the armature in opposition to the action of the coil thereon, a screw working in the core to adjust the pressure of said spring, one of the contacts of the circuit controller being mounted on said stem, a fixed terminal for the charging circuit, a flexible metallic bonding connection between said terminal and said contact, said bonding connection being sufficiently flexible to be without substantial effect on the movement of the armature, and a screw adjustably mounted with relation to the said electro-magnetic device, the other contact of the circuit controller being carried by said screw.

In testimony whereof, I have hereunto set my hand at Los Angeles, California, this 17th day of June 1909.
